United States Patent Office

Des. 211,717
Patented July 23, 1968

211,717

PASSENGER VEHICLE

Thomas L. Sherbert, Lanham, Md., and Tillison M. Sherbert, Washington, D.C., assignors to D.C. Transit System, Inc., Washington, D.C., a corporation of the District of Columbia

Filed July 20, 1967, Ser. No. 7,891

Term of patent 14 years

(Cl. D14—3)

FIG. 1

FIG. 2

FIG. 3

FIG. 6

FIG. 4

FIG. 5

FIGURE 1 is a perspective view of a passenger vehicle illustrating our new design as seen from the forward right hand corner thereof;

FIGURE 2 is a perspective view of the vehicle taken from the rear right hand corner thereof and with a rear door shown in open position;

FIGURE 3 is a perspective view of the vehicle taken from the rear left hand corner thereof with the rear door shown in closed position;

FIGURE 4 is a horizontal, cross-sectional view of the vehicle looking downwardly therein with the rear door in open position;

FIGURE 5 is a view similar to FIG. 4 except with the interior seats shown in a different arrangement and the rear door shown in closed position; and

FIGURE 6 is a cross-sectional view of the vehicle taken generally along lines 6—6 of FIGURE 5.

The dominant features of our design reside in the portions illustrated in solid lines.

We claim:

The ornamental design for a passenger vehicle, substantially as shown and described.
